ROD DESCALER

Warren Ailes, Pleasant Hills, David J. George, Bethel, and Stephen E. Tarby, Wilkinsburg, Pa., assignors to United States Steel Corporation, a corporation of New Jersey

Application May 4, 1955, Serial No. 505,874

2 Claims. (Cl. 29—81)

This invention relates to a device for descaling hot-rolled wire rod prior to drawing.

The object of the invention is to improve on known rod-descaling apparatus by providing a device which is simpler than the latter in construction and less expensive to manufacture, yet equally as effective in operation.

In a preferred embodiment, the device comprises a base with a housing or frame including a web or wall upstanding thereon having angularly disposed portions. Grooved bending sheaves are journaled on said portions to provide a circuitous path of travel for wire rod trained therearound and drawn through the device, so as to cause sharp bending of the rod in different planes resulting in fragmentation and detachment of scale remaining adherent from the hot rolling. A door is provided in one side of the housing to give access to the sheaves for threading, and the housing is cut away at the bottom on one side to accommodate a box for collecting the scale detached.

A complete understanding of the invention may be obtained from the following detailed description and explanation which refer to the accompanying drawings illustrating the present preferred embodiment. In the drawings:

Figure 1 is a plan view;

Figure 2 is an end elevation;

Figure 3 is a side elevation; and

Figure 4 is an elevation of the end opposite that shown in Figure 2.

Referring now in detail to the drawings, the device of my invention comprises generally a base-plate 10 and a housing or frame 11 upstanding thereon. The housing includes a wall or web 12 in the form of a plate with an end 13 and a side 14. The side is composed of an entry-sheave portion 15 normal to the end 13 and deflector-sheave and exit-sheave portions 16 and 17, respectively, forming a dihedral right angle with each other and disposed at approximately 45° angles with portion 15. The free edge 17a of portion 17 is bent so as to be substantially parallel with end 13. End 13 is cut out at 18 and portion 17 at 19 to accommodate a box 20 disposed on base-plate 10 for collecting scale particles.

End 13 and side-wall portion 15 are cut away at the top adjacent their intersection to form a seat for a guide block 21. The block has sockets therein to accommodate guides 22 and 23 removably held in place by screws 24. A sheave 25 is journaled on a stub shaft 26 fixed in side-wall portion 15 normal thereto so that the axis of the guides will be substantially tangent to the sheave groove at the top thereof. Thus wire rod 27 drawn through the guides will track properly in the sheave groove.

A second sheave 28 is journaled on a stub shaft 29

2

fixed in wall portion 16, normal thereto but at a level below that of shaft 26. The construction is such that the grooves of sheaves 25 and 28 at their adjacent sides are substantially tangent to a common vertical line so that rod 27 tracks properly from the first sheave to the next after bending downwardly around the former as shown in Figure 3.

A third sheave 30 is journaled on a stub shaft 31 fixed in wall portion 17 normal thereto at a level between those of shafts 26 and 29. The arrangement and construction are such that the grooves of sheaves 28 and 30 are substantially tangent at their adjacent sides to a common vertical line. Thus wire rod tracks properly from the second sheave to the third after bending 180° around the former.

Housing 11 is completed by a door 32 hinged to end 13. The door is normally held closed by a latch 33 pivoted to the bent edge 17a of side-wall portion 17, but may be opened to give access to the sheaves for ease in threading the rod therearound initially. A cut-out 34 in the top of the free edge of the door and the adjacent side wall portion permits the wire rod to be pulled straight from the top of sheave 30 by any suitable drawing means (not shown). The line along which the rod is pulled out will obviously be at a 45° angle in the horizontal plane with the line along which the rod enters guides 22 and 23.

It will be evident that rod 27, in being drawn around the sheaves 25, 28 and 30 successively, is bent back and forth in several different planes. As a result, the scale adhering thereto is thoroughly broken up and effectively detached and falls into collecting box 20. Thus the rod leaving the apparatus will be clean and scale-free, ready for drawing, coating or other processing as desired. A sloping deflector plate 35 extending along the side 14 guides any scale particles falling thereon into the box. When the box is full, it is manually removed for disposal of the collected scale and replaced by an empty box.

It will be apparent that the device of our invention is characterized by extreme structural simplicity so that it can readily be manufactured at low cost. It nevertheless performs its intended function effectively and requires no attention or maintenance beyond routine lubrication. It requires only a small amount of floor space and can thus be installed in existing plants without necessitating extensive relocation of facilities.

Although we have disclosed herein the preferred embodiment of our invention, we intend to cover as well any change or modification therein which may be made without departing from the spirit and scope of the invention.

We claim:

1. Apparatus for descaling rod comprising a base plate and a frame plate normal to the base plate, said frame plate including an entry-sheave portion, a deflector-sheave portion at about a 45° angle to the entry-sheave portion and an exit-sheave portion substantially normal to said deflector-sheave portion and extending therefrom back toward the plane of said entry-sheave portion, a sheave journaled on said entry-sheave portion, a sheave journaled on said deflector-sheave portion at a level below the first-mentioned sheave, and a sheave journaled on said exit-sheave portion at a level above said second-mentioned sheave, said sheaves being so positioned that wire rod trained therearound successively tracks accurately from each sheave to the next, said frame plate also including an end wall at the edge of the entry-sheave portion remote from the deflector-sheave portion, said

end wall extending at right angles to the entry-sheave portion, and a guide block mounted on said end wall, effective to direct entering rod onto said first-mentioned sheave.

2. Apparatus as defined in claim 1, characterized by 5 a door hinged to said end wall extending to the far side of said frame plate and spaced therefrom to a second end wall extending angularly from said exit-sheave portion and located opposite said first-mentioned end wall, said door and end walls having their lower edges spaced above 10 the base plate to admit a scale-collecting box below said sheaves.
